UNITED STATES PATENT OFFICE.

DONALD B. PERRY, OF YONKERS, NEW YORK, ASSIGNOR TO AMERICAN TELEPHONE AND TELEGRAPH COMPANY, A CORPORATION OF NEW YORK.

PRINTING-TELEGRAPH EXCHANGE SYSTEM.

Application filed November 10, 1923. Serial No. 674,016.

To all whom it may concern:

Be it known that I, DONALD B. PERRY, residing at Yonkers, in the county of Westchester and State of New York, have invented certain Improvements in Printing-Telegraph Exchange Systems, of which the following is a specification.

This invention relates to printing telegraphy and more particularly to printing 10 telegraph exchange systems.

An object of the invention is a provision of switching apparatus under the control of a plurality of printing telegraph stations for extending connections over a telegraph line 15 in either direction between said stations.

In accordance with the preferred form, the present invention contemplates the provision of machine switching apparatus associated with each end of a telegraph line 20 which is equipped for duplex operation, and controlled by each of a plurality of printing telegraph stations for extending connections between the stations in either direction over said line.

25 In the single figure of the drawing, there is shown the apparatus associated with one end of a telegraph line, and common to a plurality of printing telegraph subscribers.

In the drawing, there is shown a printing 30 telegraph subscriber's station A connected to a central station B by means of line conductors C, which terminate in machine switching apparatus and which are arranged to be extended over a telegraph line 10 to a distant station where apparatus identical to that shown in the drawing is located.

The machine switching apparatus comprises a plurality of banks of contacts D, E, 40 F, G, H and I, which are arranged to be traversed by suitable wipers, whereby desired circuits are under control of the subscribers' stations for extending desired connections. Leading from the contacts in the banks D and E are conductors which extend to the contacts of the cut-off relay individual to each of the subscriber's lines, it being of course understood that a plurality of lines similar to C extend from other subscribers' stations to the central office in 50 which the machine switching apparatus is located.

Each of the subscriber's stations is provided with a printing telegraph transmitter and receiving printer and an impulse sending device 8, the latter being employed for

the transmission of selective impulses for operating the machine switching apparatus to set up desired connections.

Assume for the sake of illustration, that the subscriber A desires to extend his line C 60 to a subscriber located in a distant city in which the telegraph line 10 terminates. Subscriber A would operate switch 5 for causing the energization of switching relay 6 which disconnects at its contacts the ground connection and the call bell 7 and connects the transmitter, printer and impulse sending device 8 in series with the line C. Following the closure of the front contacts of switching relay 6, an energizing circuit is 65 established for line relay 12 extending from grounded battery, winding of line relay 12, upper contact and armature of cut-off relay 13, right-hand armature and front contact of relay 6, transmitter and printer in series, 70 contact 9 of the impulse sending device 8, left-hand front contact and armature of relay 6, and the lower armature and back contact of relay 13 to ground. Line relay 12 is 75 energized over the circuit just traced and disconnects ground from the contact in the bank F corresponding to the calling subscriber's line, and connects ground to the first contact in the bank of contacts H. The connection of ground to the first contact in 80 the bank of contacts H establishes an energizing circuit for the slow-to-release relay 15 and the stepping magnet 16, extending from grounded battery, winding, armature and back contact of stepping magnet 16, upper winding of relay 15, first contact in the bank of contacts H and the front contact and armature of relay 12 to ground. Relay 15 prepares a locking circuit for itself and for magnet 16 extending to ground through the F wiper and bank of contacts. The contacts in the bank of contacts F should be 85 grounded for all spare lines, while the other contacts will be connected to ground through the back contact and armature of the line relay individual to each of the lines in the manner illustrated in the drawing.

On each energization of the stepping magnet 16, the back contact of the stepping magnet will be opened for causing the deenergization of this magnet, whereupon a pawl attached to its armature will act against a ratchet to cause all six wipers F to I inclu-

sive to advance one step. Inasmuch as relay 15 is of the slow-to-release type, it does not release its armatures on the opening of the contact at magnet 16. However, when the 5 back contact of this magnet is again closed, a circuit for causing its energization is established through the wiper and grounded contacts in the bank F causing the further advancement of each of the wipers. Accordingly, the wipers will be advanced to a 10 point where there is an absence of ground on the F wiper at which time the energizing circuit for the stepping magnet 16 will not be completed and the further advancement 15 of the wipers is prevented. In the particular selection chosen, the wipers would advance until they engage contact 14 which is connected to the back contact of line relay 12 and which, owing to the operation of this 20 relay, has absence of ground thereon.

When the terminals of the calling line are reached by the wipers, the slow-to-release relay 15 will then release opening the circuit of the stepping magnet 16 and closing at 25 its upper contact a circuit extending from grounded battery, winding of control relay 18, upper armature and contact of relay 21, uppermost armature and back contact of relay 15, wiper and contacts in the bank 30 G, windings of cut-off relays 19, 13 and 20 in series to ground. Control relay 18 and cut-off relays 19, 13 and 20 will be energized over the circuit just traced. The cut-off relays, there being one of these relays associated with each of the subscriber's lines, disconnect all the associated line relays and connect all the individual lines to the contacts in the banks D and E allotted to the 35 particular subscribers' stations. As for example, the cut-off relay 13 connects through 40 its front contacts to the bank of contacts D and E the line C extending from the subscriber's station A. The control relay 18 prepares a circuit for locking ringing cut-off relay 22 and energizing relay 23 and 45 also transfers the circuit extending from the armature of differential relay 24 from the relay 21 to the release circuit through the bank of contacts H. Since the wipers 50 have stopped at the terminals corresponding to the line C, only that subscriber's line will be connected through to the ringing cut-off relay 22. The release of the line relay 12 will have no effect as relay 15 is now 55 released, thereby preventing the reestablishment of the stepping circuit.

Ringing current will now be transmitted 60 intermittently through the upper winding and upper back contact of ringing cut-off relay 22, through the D wiper and subscriber's terminal over the line C returning through the terminal and wiper on the connected contact in bank E through the armature 65 30 and associated back contact of the ringing cut-off relay 22 to ground. The

ringing cut-off relay 22 will be operated immediately as this relay operates upon the establishment of a direct current path which is established upon the energization of cut-off relay 13. 70

Immediately upon the operation of ringing cut-off relay 22 a locking circuit therefor is established from grounded battery, lower armature and front contact of control relay 18, winding of relay 23, lower 75 winding and lowermost front contact and armature of cut-off relay 22 to ground. The ringing cut-off relay 22 and the relay 23 will be held energized until the calling subscriber disconnects. The ringing cut-off relay 22 connects the D wiper to the control winding of the pole changer relay 27 through the upper winding of the differential relay 24 and the upper armature and contact of control relay 29, while the 80 wiper of the E set of contacts is connected through to the lower winding of differential relay 24. The subscriber A is now connected to the duplex apparatus associated with the telegraph line 10. 85

Differential relay 24 which had previously been locked up through resistance 25, which is disconnected upon the energization of cut-off relay 22 now releases as equal current flows through both of its windings. The 90 release of differential relay 24 has no effect at this time as its front and back contacts are both opened. Relay 23 is slow-to-operate and does not energize until after the differential relay 24 has released. It 95 connects ground to the front contact of the differential relay 24, thus preparing a circuit for releasing the selector switch when the differential relay operates as described later. 100

As previously stated, the subscriber's line C is connected through the contacts in the banks D and E and the wipers individual thereto to the apparatus associated with the telegraph line 10, which apparatus is now 110 under control of the subscriber A. 105

The subscriber A now operates the impulse sending device 8 for opening and closing contact 9 a predetermined number of times in accordance with the number of 115 the called for subscriber's station, whereby the circuit of the control winding on the pole changer relay 27 is opened and closed. Due to the opening and closure of the energizing circuit of the pole changer relay 120 27, impulses are transmitted over the telegraph line 10 in accordance with the operation of the impulse sending device 8. These impulses pass over the telegraph line 10 and traverse the windings of the receiving 125 relay 28 located at the opposite end of the telegraph line 10. Receiving relay 28 responds to such impulses and controls the operation of control relay 29 thereby causing the energization and deenergization of 130

the differential relay 24 in accordance with the received impulses. As the impulses are received from the line, the differential relay 24 responds and each impulse will release this relay and close a circuit which may be traced from grounded battery, winding of stepping magnet 16, lower contact and armature of relay 15, winding of slow-to-release relay 21, upper back contact and armature of relay 18, armature and back contact of differential relay 24 and the lowermost back contact and armature of relay 22 to ground. The closure of the circuit just traced at the back contact of the differential relay 24 causes the operation of stepping magnet 16 for advancing the wipers to the terminals corresponding to the number of impulses transmitted over the telegraph line 10 due to the operation of the impulse sending device 8. When these impulses have ceased, slow-to-release relay 21 releases, whereby the energizing circuit is established for the control relay 18 and the cut-off relays corresponding to those shown in the drawing to associate with subscriber's lines terminating at the station in which the other end of the telegraph line 10 terminates.

The cut-off relays connect all subscribers' lines to their respective terminals in the D and E banks and disconnects all line relays as previously described. The selected line will, however, be connected through the wipers individual to the D and E bank of contacts to the ringing cut-off relay 22. Ringing current will be transmitted intermittently over one side of the subscriber's line for causing the operation of the call bell individual to the called-for subscriber's station. The called-for subscriber due to the operation of the call bell is advised that another subscriber desires to communicate with him telegraphically and that the printer set should be connected with the line conductors by the operation of a switch corresponding to 5 which causes the operation of a switching relay for connecting the transmitter and printer in series with the line conductors. As in the case of the outgoing calls when the switching relay is energized, a circuit for direct current through the upper winding of the ringing cut-off relay is completed, whereby this relay is energized and locked up for disconnecting the source of ringing current 26. Relay 22 also removes the resistance 25 from in series with the upper winding of the differential relay 24 and establishes the circuit to the called for subscriber's line. On this operation relay 24 releases and relay 23 operates for performing functions similar to that described at the outgoing end and the two subscribers are now connected and may communicate telegraphically by the operation of their printing telegraph apparatus.

When the calling subscriber A disconnects his printer equipment, by the opening of switch 5 after a communication is completed or in abandoning a call, ground is connected to one side of the line circuit C, 70 and the other side of this line circuit is left open to direct current. This action operates the differential relay 24 over a circuit extending from battery, lower winding of differential relay 24, front contact of 75 armature 30 of ringing cut-off relay 22, wiper and connected contact in the bank E, lower front contact and armature of cut-off relay 13, left-hand armature and back contact of relay 6 to ground. The differential relay 24 closes a circuit for the slow-to-release relay 15 and the stepping magnet 16 through the bank of contacts H and the upper front contact and armature of control relay 18. Relay 15 will operate over the circuit 80 just traced and will lock itself up through the wiper and contacts in the bank F which are all grounded at this time. The stepping magnet 16 will operate and step the wipers around to their normal position. Due to 85 its slow-to-release feature, relay 15 will remain operated during the intervals when the stepping magnet 16 opens its circuit at its armature. The relay 15 opens at its upper armature the energizing circuit of the control relay 18 and the cut-off relays which are now released. The cut-off relays disconnect all subscribers' lines from the bank 90 of contacts D and E to prevent the operation of the call bells at each of the stations 100 as the wipers rotate over the respective contacts. The release of the control relay 18 opens the locking circuit of the ringing cut-off relay 22 and relay 23, which are thereupon released, reconnecting the resistance 105 25 in circuit with the upper winding of the differential relay 24.

When the called subscriber disconnects, ground is connected to one side of the line circuit, leaving the other side of this line 110 circuit open to direct current. The restoration of the selector switch to normal is similar to that described in connection with the disconnection of the calling subscriber. Further description is therefore thought unnecessary.

During the interval from the time the subscriber A disconnects the printer equipment from the line to the moment that the resistance 25 is connected in circuit with the upper winding of the differential relay 24, the pole changer relay 27 is deenergized for transmitting over the telegraph line 10 a spacing impulse. This spacing impulse upon being received at the incoming end of the line causes the operation of the receiving relay 28 and the release of the control relay 29. The differential relay 24 at the incoming end of the line will be energized 120 for causing the energization of slow-to-re-

lease relay 15 and the stepping magnet 16, as previously described. The incoming selector will thus be restored to its normal position, the restoration of the selector at the 5 outgoing end of the line being similar to that previously described.

It often happens that one subscriber may disconnect before the other, thereby restoring the selector switch to normal before the 10 second subscriber disconnects. Due to the fact that the telegraph circuit is opened for a short interval after a subscriber disconnects, the differential relay of the selector associated with the line of the first subscriber 15 to disconnect, will release and later operate when the telegraph line is closed. This, in turn, operates and releases relay 21 and the stepping magnet 16, thereby stepping the wipers of the selector at the first 20 station to disconnect on to the second set of contacts. A circuit is at once completed to operate relay 15 and restore the selector to normal in the manner previously described.

It occasionally occurs in regular service 25 that the telegraph line may be opened for an interval. This may be caused by any one of a number of conditions such as an accidental operation of a key, "a swing" on the line, etc. The effect at both stations of such 30 an open circuit would be similar to the delayed disconnect, previously described. The duration of the open condition will not affect the procedure as long as the circuit closes eventually, at which time it will 35 be restored to normal. It is thus seen that the circuit provides for a return to normal after a false or accidental opened circuit, as well as a delayed disconnect by either subscriber.

40 Should the subscriber A operate the impulse sending device 8 in error, as to select a set of unused terminals, a clear-out circuit is provided whereby the selector will restore the system to normal. All of the terminals 45 in the bank I corresponding to the unused lines are grounded and when the wiper stops on any one of these terminals and relay 21 is released, relay 15 is energized through its lower winding, restoring 50 the selector to its normal position.

Should the calling subscriber disconnect the printer equipment before the selector has reached the terminals corresponding to the calling line, the wipers will continue to rotate until they again reach the normal position. If the call is abandoned after the 55 line has been seized and before the operation of the impulse sending device 8, the outgoing selector will be released in the normal manner and an impulse will be transmitted 60 over the telegraph line 10 causing the wipers at the distant station to make one revolution.

When the telegraph line is in use, all of 65 the cut-off relays will be energized at both

stations, thus removing the battery and ground connections from all of the local lines. If a subscriber attempts to extend a connection at this time, it will be found that the line circuit is in use and the action of the 70 receiving printer will serve to notify such subscriber of this condition. The same condition exists when the subscriber's line is busy.

Although the invention has been described 75 with reference to a particular system, it is of course obvious that various modifications may be made without departing from the spirit and scope of the present invention.

What is claimed is:

80 1. In a telegraph system, a plurality of printing telegraph stations, each provided with a receiving printer and transmitter, a telegraph line, and switching mechanism common to said stations and under the control of any of said stations for extending connections in either direction over said line between said stations.

85 2. In a telegraph system, a plurality of printing telegraph stations, each provided with a receiving printer and transmitter, a telegraph line, and a single switching mechanism common to said stations and under the control of any of said stations for extending connections in either direction over 90 said line between said stations.

95 3. In a telegraph system, a plurality of printing telegraph stations, each provided with a printing telegraph transmitter and receiving printer, a local line individual to each of said stations extending therefrom to a central station, a telegraph line terminating at said central station, switching mechanism normally disconnected from said local lines, and means operative upon the connection of the transmitter and receiving printer with any one of the local lines for causing said switching mechanism to automatically extend the line from said station 100 to said telegraph line.

105 4. In a telegraph system, a plurality of printing telegraph stations, each provided with a printing telegraph transmitter and receiving printer, a local line individual to each of said stations extending therefrom 110 to a central station, a telegraph line terminating at said central station, switching mechanism normally disconnected from said local lines, switching mechanism directly connected to said telegraph line, 115 means responsive to the connection of the transmitter and receiver with a local line for automatically causing the operation of said switching mechanism to a predetermined point, and means operative due to the positioning of said switching mechanism to a predetermined point for connecting all of said local lines to said switching mechanism 120 and extending the connected station through 125 to the telegraph line.

5. In a telegraph system, a plurality of telegraph stations, each provided with a receiving printer and transmitter, a telegraph line, switching mechanism common to said stations and under the control of any of said stations for extending connections in either direction over said line between said stations, and means operative upon a momentary accidental opening of said line for restoring said switching mechanism to normal to again be in readiness for the extension of further connections.
6. In a telegraph system, a plurality of telegraph stations, each provided with a receiving printer and transmitter a telegraph line, switching mechanism common to said stations and under the control of any of said stations for extending connections in either direction over said line between said stations, and a differential relay associated with each end of said telegraph line and operative upon a momentary accidental opening of said line for restoring said switching mechanism to normal to again be in readiness for the extension of further connections.

In testimony whereof, I have signed my name to this specification this 8th day of November, 1923.

DONALD B. PERRY.
